US00D456375S

(12) **United States Design Patent** (10) Patent No.: **US D456,375 S**
 (45) Date of Patent: ** Apr. 30, 2002

(54) **HANDSET**

(75) Inventors: **Hanna Vuolteenaho**, Copenhagen K (DK); **Tapani Jokinen**, Oak Park, CA (US); **Pertti Salmi**, Oulu (FI)

(73) Assignee: **Noki Mobile Phones Limited**, Espoo (FI)

(**) Term: **14 Years**

(21) Appl. No.: **29/134,755**

(22) Filed: **Dec. 29, 2000**

(51) LOC (7) Cl. **14-03**

(52) U.S. Cl. **D14/138**

(58) Field of Search **D14/137, 138, D14/218, 147-148, 247-248, 144, 250, 341-347; 379/433, 434, 419, 420, 428, 440; 455/550-575, 90**

(56) **References Cited**

Primary Examiner—Jeffrey Asch

(74) Attorney, Agent, or Firm—Perman & Green, LLP

(57) **CLAIM**

The ornamental design for a handset, as shown and described.

DESCRIPTION

FIG. 1 is a bottom plan view of a handset showing our new design;

FIG. 2 is a right side view thereof;

FIG. 3 is a front elevational view thereof;

FIG. 4 is a left side view thereof;

FIG. 5 is a top plan view thereof;

FIG. 6 is a front, bottom, right side perspective front view thereof;

FIG. 7 is a top, rear, right side perspective rear view thereof; and,

FIG. 8 is a rear elevational view thereof.
